UNITED STATES PATENT OFFICE.

FLOYD L. SCOTT, OF HOUSTON, TEXAS, ASSIGNOR TO HUGHES TOOL COMPANY, OF HOUSTON, TEXAS.

PIPE WRENCH.

Application filed April 17, 1922. Serial No. 554,038.

To all whom it may concern:

Be it known that I, FLOYD L. SCOTT, a citizen of the United States, residing at Houston, Harris County, Texas, have invented a certain new and useful Improvement in Pipe Wrenches, of which the following is a full, clear, and exact description, such as will enable others skilled in the art to which it appertains to make and use the same.

My invention relates to an improvement in pipe wrenches ordinarily used in handling pipe during the operation of well drilling. The improvement consists in an efficient means of supporting the wrench in the derrick in such manner that the position of the wrench may be easily reversed.

The object of the invention is to provide a means of suspending a wrench within the derrick so that the said wrench may be reversed in position so as to operate in either direction without unnecessary amount of manipulation.

Another object is to provide a suspending means for a pipe wrench which is strong and rugged in construction and which is not in the way of the operator while the wrench is in use.

Referring to the drawings herewith, wherein like numerals of reference are applied to like parts throughout the several views; Fig. 1 is a top plan view of a pipe wrench whereon my improvement is employed; Fig. 2 is a transverse section on the line 2—2 of Fig. 1; Fig. 3 is a view similar to that of Fig. 1, with the wrench in reversed position; and Fig. 4 is a transverse section on the line 4—4 of Fig. 3.

In the ordinary type of pipe wrench now customarily employed in handling the pipe in well drilling, the jaws are so arranged as to grip the pipe only when rotated in one direction. If it is desired to rotate the pipe in the opposite direction, the wrench must be reversed or turned upside down, so that the jaws will properly engage the pipe in the reverse motion. This type of wrench is necessarily very heavy to obtain sufficient strength and must therefore be suspended in the derrick.

With the ordinary means of suspending the wrench this reversing of the position of the wrench cannot be readily accomplished and it is therefore usual to employ

this type of wrench or tongs for working in one direction only.

I have devised a type of suspending means for a pipe wrench which allows the wrench to be very quickly and easily reversed in position. In the drawings I have shown my invention applied to a pipe wrench having a handle 5, the forward end of which is bent laterally and formed with an opening to receive a pin 6, providing a pivot for a wrench jaw 7, to the other end of which a second jaw 8 is pivotally secured by means of a pin 9. The jaw 8 has its forward end hooked, as shown at 10, for engagement with a yoke or latch member 11. Said latch member is in the shape of a link 70 having an opening 23 therethrough to receive the hooked end of the jaw 8. A handle 13 is provided on the jaw 8 to facilitate the handling thereof and the handle 14 on the link or latch member 11 accomplishes the same purpose in regard to the latch. The latch is pivoted about centrally with the line of the handle by means of a pin 12. Each of the jaws is provided on its gripping face with a transverse tooth 15, by means of which said jaw may most efficiently engage the pipe. In this type of wrench it will be obvious that when the pipe has been gripped by the two jaws 7 and 8 and the yoke or latch member has been engaged with the hook 10 upon the jaw 8, the movement of the handle in a counter-clockwise direction as seen in Fig. 1, will serve to tighten both of the jaws against the pipe, by means of the offset arrangement of the attachment of the jaw 7 and the latch 11 with the handle. A movement of the handle in the opposite direction will only serve to loosen the jaws and release the pipe. Hence, with the wrench in a position shown in Fig. 1, the pipe can only be rotated in a counter-clockwise direction as viewed from above.

In order that the wrench may be turned the other side up and thrown into position shown in Fig. 3, the novel suspending device constituting my invention has been devised. On the side of the head of the handle away from the pivot pin 12 of the latch I have formed a securing means for the suspending rod 16. This attaching means comprises a bracket formed on the side of the handle and extending away therefrom and

formed into two spaced lugs or ears 17 between which may be received the lower end of the suspending rod 16. To engage this rod a transverse pin 18 connecting with the lugs 17 serves as a pivotal attaching support. On each side of the wrench handle the attaching bracket is extended laterally and formed into posts 19 and 20 having hooked ends to engage with a link 21 on the rod 16. The upper end of the suspending rod 16 is recurved to form an attaching eye 22 for a cable.

In the operation of my device the pipe is received between the jaws of the wrench and the jaws latched into position. The link 21, which is slidable on the rod 16, is engaged over the post 19 in the position shown in Figs. 1 and 2. The link 21 is of such length as to cause the rod 16 to set at an angle to the upper face of the wrench as shown in Fig. 2. This brings the upper end 22 thereof approximately over the center of gravity of the wrench and the tendency of the wrench will then be to hang in a horizontal position. When the wrench has been operated with this form of support, and it becomes desirable to rotate the pipe in an opposite direction, the link 21 may be released from the post 19 by raising upwardly on the handle 14, thus swinging the wrench on the pivot formed by the pin 18 until the link 21 is loosened so that it may be moved away from the hooked end of the post 19. The wrench will then drop downwardly and may be swung up on the opposite side of the rod 16 into the position shown in Fig. 4. The link 21 may then be engaged over the opposite hook 20 as shown in that figure, and the wrench will again be supported in horizontal position with the upper end of the rod 16 approximately over the center of gravity of the wrench in this position. The wrench may then be applied to the pipe and the pipe rotated in a direction the reverse to that accomplished with the wrench in the first position.

The advantages of this suspending means lie largely in the fact that the suspending attachment does not interfere with the efficient operating of the wrench in use and will sustain the wrench in horizontal position at all times. The process of reversing the wrench so that the pipe may be turned in an opposite direction may be very quickly and easily performed and without any danger of injury.

Having thus described my invention what I claim as new and desire to protect by Letters Patent is:

1. In a pipe wrench comprising a handle and pipe engaging jaws thereon opening at one side of said handle, the combination of a suspending means comprising an attaching pin secured on the side of said handle opposite the opening portion of said jaws, a supporting rod pivotally secured to said pin, and means to detachably hold said rod at an angle to the upper side of the said wrench so as to bring the upper end of the said rod approximately over the center of gravity of said wrench. 60

2. In a pipe wrench comprising a handle and pipe-engaging jaws thereon, the combination of a suspending means comprising a rigid rod pivotally secured at one side of said handle, a rod-engaging means on said handle, and means on said rod cooperating therewith to hold said rod at an angle to the side of said wrench to bring the upper end of said rod approximately over the center of gravity of said wrench. 75

3. In a pipe wrench, a handle, a flattened head thereon, jaws pivoted to said head, a supporting means on one edge of said head comprising a lateral attaching pin, oppositely extending posts having hooked ends thereon, a rigid suspending rod pivoted to said pin, and a link slidable on said rod and adapted to engage either of said posts to hold said rod at an angle to the flattened head in the manner described. 85

4. In a pipe wrench, a handle, pipe-engaging jaws thereon, a lateral plate on said handle adjacent said jaws, a rigid supporting rod pivoted to said plate, attaching posts extending in opposite directions approximately vertically from said plate, and means to secure said rod detachably to either of said posts to bring the upper end of said rod approximately over the center of gravity of said wrench. 95

5. In a pipe wrench, a rigid supporting rod secured pivotally to one side thereof, posts on said wrench extending laterally therefrom, and a detachable connection between said rod and said posts whereby said wrench may be supported with either side presented upwardly as desired. 100

6. In a pipe wrench, a rigid supporting rod, a wrench handle, means pivotally attaching said rod to said handle, and additional means co-operating with said rod to detachably retain said wrench with either side presented upwardly as desired. 110

In testimony whereof, I hereunto affix my signature, this the 12th day of April, A. D., 1922.

FLOYD L. SCOTT.
